WALL PLAQUE

Martin Henfield, Long Island City, N. Y.

Application October 20, 1952, Serial No. 21,900

Term of patent 7 years

(Cl. D29—23)

To all whom it may concern:

Be it known that I, Martin Henfield, a citizen of the United States, residing at Long Island City, New York, in the county of Queens and State of New York, have invented a new, original, and ornamental Design for a Wall Plaque, of which the following is a specification, reference being had to the accompanying drawing, forming part thereof.

In the drawing:

Fig. 1 is a front elevational view of a wall plaque, showing my new design;

Fig. 2 is a vertical sectional view taken on line 2—2 of Fig. 1; and

Fig. 3 is a top plan view of the same.

I claim:

The ornamental design for a wall plaque, as shown.

MARTIN HENFIELD.
